Inventor:
Emile Berliner,

Wolft Hallehales
Att'l'ys.

UNITED STATES PATENT OFFICE.

EMILE BERLINER, OF WASHINGTON, DISTRICT OF COLUMBIA.

WALL.

Application filed March 24, 1926. Serial No. 97,012.

The invention relates to walls, and more specifically to a wall structure comprising a plurality of hollow cells or depressions immediately beneath the surface thereof and imparting to the surface of the wall the characteristics of diaphragms, possessing marked qualities of resonance and sound reflection and at the same time counteracting reverberation.

10 The invention is particularly applicable to masonry walls, such as those of auditoriums, theaters, concert halls, churches and the like, where good acoustics is a prime consideration. In masonry walls as at present constructed the solidity of the structure promotes reverberation, and such walls are found to be almost entirely lacking in that resonant property so essential for the production of a good acoustic effect.

15

20 My prior U. S. Patent No. 1,573,475 discloses a facing for walls comprising a plurality of independent vibratory diaphragms, which are affixed to the surface of the wall. In the present invention, however, hollow 25 cells are formed in the wall during the construction thereof, the members used in forming these cells being in no sense vibratory diaphragms, but serving simply as molds or supports for forming the hollow cells, which 30 themselves impart the desired resonant quality to the wall.

An object of my invention is to provide a structure which is permanent and non-inflammable and which, at the same time, 35 possesses the desired acoustic properties of wood walls, being of vibratory character and a good reflector of sound.

A further object is to provide a cellular wall structure so formed that a resonant 40 quality is imparted to the surface of the wall.

Other and further objects will be apparent from the following description with reference to the accompanying drawing, in 45 which:

Fig. 1 is a view, partly in section, of a wall provided with the cell-like members comprising the present invention;

Fig. 2 is a sectional view taken along line 50 2—2 of Fig. 1;

Fig. 3 is a perspective view of one of the cell-like members;

Fig. 4 is a perspective view of a modified form of cell-like member;

55 Fig. 5 is a plan view, partly in section, of a modified form of wall structure; and

Fig. 6 is a vertical section of the structure shown on Fig. 5.

Referring more particularly to the drawings:

60 The coarse plaster, or the like, base surface 1 has a plurality of members 2 attached thereto, as shown diagrammatically on Fig. 1. The members 2 each comprise a base portion and a rim 3 designed to space 65 the base portion from the surface 1, and they are preferably of circular form as shown, for the purpose of anchoring them to the surface 1, as described hereinafter. I do not, however, restrict the invention to 70 the use of circular members; those of any other suitable form and dimensions, for example, hexagonal, octagonal or the like, may be used with equally good results. The members 2 are preferably made of cardboard or 75 the like, and are affixed to the surface 1 and to each other by means of nails or other suitable and convenient fastening means for holding them temporarily in position. These cell-like members may also be made of wire 80 mesh fabric, as shown on Fig. 4, foraminous metal or other suitable material. When applied to the unfinished surface of a wall as set forth above, the cell molds 2 are covered with a finishing coat 4 of so-called acoustic 85 plaster, that is, a mixture of plaster, cement or the like, and a filler, such for example, as sawdust, etc., adapted to aid in producing the desired resonance. Ordinary plaster or cement may also be used as a finishing 90 coating, but the acoustic plaster is preferable. This cementitious coating fills in the spaces between adjacent members 2, securely anchoring them to the surface 1, and at the same time completely covers the members 2, thus providing a finished and unbroken wall surface. The members 2 simply 95 serve as molds or supports for the formation of the cellular spaces in the wall. Their removal, after the finishing cementitious coat 100 has been applied, would be impractical, if not impossible, and since their presence does not impair the acoustic properties of the finished wall, they are allowed to remain, serving to some degree as a reinforcement 105 for the wall.

A modification of my invention is shown on Fig. 5 and 6, wherein depressions, the equivalents of the cellular spaces formed in the previously described embodiment, are 110 made in the unfinished or base surface of a wall. These depressions 5 are shallow and

are covered with a sheet of fabric of any kind, paper, cardboard wire gauze or foraminous metal, etc., as indicated at 6 on the drawing. The whole is then covered with 5 a layer of acoustic plaster or other cementitious coating, as described hereinbefore, and results in a resonant wall surface which, however, has a finished appearance.

From the foregoing it will be apparent 10 that I have provided a wall structure which is permanent, fireproof and inexpensive, and which possesses the marked acoustic properties of wood walls.

I do not herein claim the specific structure 15 of an auditorium wall as described and claimed in my U. S. Patent No. 1,573,475, of February 16, 1926, but I do claim:—

1. A wall structure formed adjacent its 20 surface with a plurality of hollow cell members covered with a resonant cementitious material.

2. A wall structure comprising a layer of plaster, a plurality of hollow molds affixed thereto, and a finish layer of acoustic plaster

covering said molds and extending between 25 them for securing them permanently to the wall.

3. In an auditorium or the like, a wall covered with cells which are affixed thereon by a layer of cementitious material which 30 covers said cells and thereby provides vibratory partitions which serve as diaphragms.

4. In an auditorium or the like, a wall, a plurality of wire mesh cell-like members affixed thereto, said members being embedded 35 in and affixed to the wall by a layer of cementitious material, whereby the finished wall will contain a plurality of vibratory partitions which serve as diaphragms.

5. A construction which comprises cell- 40 like members affixed to a surface of a chamber and covered with a resonant cementitious material.

6. A wall structure formed adjacent its 45 surface with a plurality of hollow cells covered with a resonant cementitious material.

In testimony whereof I affix my signature.
EMILE BERLINER.
